ELECTRIC SUBMERGIBLE PUMP UNIT

Armais Arutunoff, Tulsa, Okla.

Application February 27, 1931, Serial No. 518,799

6 Claims. (Cl. 103—46)

My invention consists in new and useful improvements in deep well pumps and relates particularly to reciprocating pumps operated by a vertical submergible electric motor-driven unit.

5 While it is desirable in many instances to employ a reciprocating pump in connection with an electric motor located in the well, there have been numerous difficulties in obtaining a reciprocating motion suitable for the action of a pump, 10 that is, a long stroke with a substantially low number of strokes per minute. Ordinarily a crank operated pump cannot be employed in this connection on account of the small diameter of 15 the crank which is necessarily restricted by the diameter of the well which, in deep oil wells is usually from four to eight inches. A short three to five-inch stroke will necessitate, for the required power, such a high number of strokes as to interfere with the valve action of the pump.

20 One of the objects of my invention is to overcome the disadvantages heretofore encountered in apparatus of this character, and to this end I provide means for producing a long stroke pump action from a submergible electric motor with 25 a vertical shaft.

Another object is to provide means for protecting all the working parts from the harmful action of the well fluid and to embody all of said working parts of the pumping mechanism in one unit 30 directly connectible to the motor.

A still further object of my invention is to provide means for protecting the pump plunger or piston and cylinder from the abrasive action of sand and grit, and thus prolong the life and 35 facilitate the effective operation of the apparatus.

With the above and other objects in view which will appear as the description proceeds, my invention consists in the novel features herein set forth, illustrated in the accompanying drawings, 40 and more particularly pointed out in the appended claims.

Referring to the drawings in which numerals of like character designate similar parts throughout the several views,

45 Fig. 1 is a view in side elevation partially broken away showing the complete assembly.

Fig. 2 is an enlarged view of the upper portion of the pump unit as indicated in Fig. 1.

Fig. 3 is a sectional view taken on line 3—3 50 of Fig. 2.

Fig. 4 is an enlarged sectional view of the intermediate portion of the apparatus as indicated in Fig. 1.

Fig. 5 is a sectional view taken on line 5—5 55 of Fig. 4.

Fig. 6 is an enlarged detail sectional view of the submergible motor unit as indicated in Fig. 1.

Fig. 7 is a sectional view taken on line 7—7 of Fig. 6.

Fig. 8 is an enlarged detail sectional view of 60 the grease sealing means for the pump piston or plunger.

Fig. 9 is a transverse sectional view taken on line 9—9 of Fig. 5.

Fig. 10 is an enlarged view of one form of automatic tension device for the chain drive, and

Fig. 11 is a view of a modification.

In the drawings, 1 represents a motor housing carrying a vertical type submergible electric motor 2 which drives a vertical motor shaft 3, 70 the upper end of which is coupled as at 4 to the drive shaft 5 located in the lower end of a second housing 6, suitably secured to the upper extremity of the motor housing 1, said housing 6 being completely filled with lubricating oil. The drive shaft 75 5 carries at its upper end a pinion 7 which, through the medium of a bevel gear 8 drives a transverse short shaft 9 which runs in a suitable bearing housing 10, rigidly supported adjacent the lower extremity of a vertically extending 80 beam 11 which extends substantially the entire length of the intermediate housing 6.

The transverse shaft 9 carries a sprocket 12, adapted to operatively engage a suitable endless chain 13 which engages an idler sprocket 14 85 mounted on a second transverse shaft 15 a predetermined distance above the shaft 9. The shaft 15 is carried in a suitable bearing housing 16 which is slideably mounted in the vertical slot 17 on the beam 11, said housing being secured in 90 place on the beam by suitable bolts 18 extending through slots 19 in the frame of said housing. In order to maintain a constant tension on the sprocket chain 13, I provide an eccentric cam 20 rotatably secured to the beam 11 by means of a 95 bolt 21, the periphery of said cam engaging the lower extremity of the frame of the bearing housing 16 as at 22, Fig. 10. A cable or strap 23 extends around the periphery of the cam 20 and is rigidly secured thereto at one end, its other end 100 running off the cam surface and being connected to one end of a suitable coil spring 24, the other end of which is fastened to a bracket 25 mounted on the beam 11, whereby there is a constant tendency to rotate the cam 20 in counter-clockwise 105 direction on the pin 21, which causes an upward pressure on the bearing housing 16, thus maintaining a tension on the chain 13.

26 represents an arm secured at one end to a link of the chain 13 by a stud or finger 27, the 110

other end of said arm being operatively connected as at 28 to a guide shoe 29 which reciprocates in a vertically disposed track formed by guide ribs 30. The guide shoe 29 is provided with an 5 outwardly projecting shoulder or ledge 31 which operatively supports the lower end of a pump stem or plunger 32, the upper end of which projects beyond the casing 6 into the pump cylinder 33 hereinafter described.

10 The upper end of the intermediate housing 6 is closed by a suitable cover 34 apertured to accommodate the stem of the plunger 32 and at its lower extremity by a base 35, whereby the working parts just described are completely protected from the surrounding fluid in the well.

15 The pump cylinder 33 is connected to the cover 34 through the medium of a pump packing unit 36 which, as will be best seen from Fig. 8, comprises a cylindrical housing divided transversely 20 into two compartments by a partition 37, the upper compartment comprising a packing chamber 38 and the lower compartment forming a mercury cavity 39, the purpose of which will be hereinafter set forth. The lower end of the packing unit 36 is threaded as at 40 to engage a second packing member and guide 41 for the stem 32, said last named packing member consisting of a cylindrical housing threaded at 42 to engage a suitable aperture in the cover 34. Within the 25 packing member 41, I provide suitable packing sleeves 43 and 44, spaced apart as at 45 to form a grease cavity for lubricating and packing the plunger 32.

30 The housing 41 is apertured at 46 adjacent the cavity 45, which aperture is in communication with a port 47 in the cover 34, which in turn leads from a grease well 48 formed in said cover. The grease well 48 is internally threaded to receive complementary threads on the lower end of a 35 grease gun 49, the latter comprising a tubular grease receptacle or cylinder within which is located a plunger 50 maintained under a normally downward pressure by a suitable coil spring 51, whereby when said cylinder is filled with grease, 40 there is a constant tendency for said plunger 50 to force said grease through the port 47 into the cavity 45 and around the pump stem 32. 52 represents a suitable fitting for charging the grease gun 49.

45 The upper end of the pump cylinder 33 is threaded to engage a hanger 53 (Fig. 3), said hanger being provided with a substantially U-shaped conduit or port 54 which merges centrally into a discharge conduit 55. One end of the conduit 54 is in communication with the pump cylinder 33, while the other end of said conduit is connected to a suction valve housing 55 mounted on the upper end of the grease gun 49, said housing containing a suitable suction valve 56 controlling a conduit 57 provided with a plurality of inlet ports 58 around its periphery.

50 The central conduit 55 of the hanger 53 is in communication with a discharge valve housing 59 which is secured to the upper end of said hanger, said housing containing a suitable discharge valve 60. The other end of the housing 59 is in communication with the discharge line 61 through the medium of a surge chamber 62, the latter comprising an enlarged cylinder within 55 which is provided a reciprocating floating plunger 63 which completely fills the cylinder 62 transversely, but is of substantially lesser vertical dimensions. The piston 63 is apertured centrally to receive a discharge conduit 64 which is in communication with the discharge line 61 at its upper

end, and with the discharge valve housing 59 at its lower end, said conduit 64 being provided with a port 65 whereby its interior is in communication with the lower portion or fluid pressure area of the surge chamber 62 below the piston 63 for the purpose hereinafter set forth.

80

The upper portion or compression area of the surge chamber is provided with a valved port or conduit 66 whereby that portion of the chamber above the piston 63 may be charged with compressed air before installation. It will be noted that in order to prevent the escape of the compressed air past the plunger 63 I may provide said plunger with suitable expansion cups and furthermore by providing a column of grease 67 on the top of said plunger.

90

To prevent the abrasive action of sand and grit on the piston 32 and the cylinder 33 within which it reciprocates, I provide a column of mercury or other suitable fluid 68 in the pump cylinder adjacent the upper end of the piston 32. It will be noted that sand or any other foreign matter floats on the mercury column and is thus prevented from working in between the moving parts, and any mercury which may leak past the pump packing 38, will be entrapped in the mercury cavity 39 from whence it may be withdrawn through the opening 39a for further use.

95

In order to avoid the possibility of the entrance of the surrounding well fluid into the lubricating oil which fills the intermediate housing 6, a trap 69 is provided, said trap consisting of a closed chamber located within the housing 6 and having two fluid conduits 70 and 71, the former being open to the surrounding well fluid at its upper extremity and terminating at its lower end at the bottom of the trap as shown in Fig. 5, while conduit 71 connects the lower portion of the housing 6 with the upper portion of the trap. It will be noted that with this arrangement, the displacement of the reciprocating plunger 32 cannot cause loss of oil in the housing 6, as the oil discharged in the trap through conduit 71 by the in-stroke of the plunger 32 is taken back into the housing 6 by the next out-stroke of the plunger, the conduit 70 accommodating the displacement from the trap caused by the in-flowing oil on the in-stroke of the plunger 32.

105

72 represents an electrical cable which leads from a suitable source of supply through the 125 housing 6 to the motor 2 in the housing 1.

In operation the motor 2 drives the shaft 3, which by means of the pinion and bevel gear 7 and 8 respectively, transmits power through shaft 9 and sprocket wheel 12, to the endless chain 13 130 running on the sprocket wheels 12 and 14. The power from the chain is in turn transmitted through the arm 26 to the pump stem 32 which is reciprocated vertically in the pump cylinder 33 as the chain travels around the sprocket wheels. 135 As the distance between the sprocket wheels 12 and 14 may be regulated to any desired degree, it is obvious that any length of pump stroke may be obtained by my improved arrangement.

The chain 13 is held in proper tension by the 140 action of the eccentric cam 20 which under the load of spring 24, turns on the stationary pin 21, normally tending to increase the distance between the sprockets and thus automatically compensating for any slack which may have developed 145 in operation from wear or stretching of the chain.

At this point attention is directed to Fig. 11 which illustrates a modified form of tension device. Instead of the cam 20 I may employ a loaded screw spring arrangement comprising a 150

vertically disposed screw member 73 threaded for a portion of its length at its upper end to engage suitable threads in a transverse support 74, its lower extremity being reduced and terminating in

- 5 a head 76. A coil spring 75 encircles the lower portion of the screw 73 with its upper end fixed to an intermediate point 77 on said screw, the lower end of said spring being rigidly secured to a second support 78 within which the reduced end 10 of said screw is rotatably mounted. The upper end of the screw 73 abuts the lower portion 22 of the frame 16 and when the head 76 is rotated in counter-clockwise direction, the frame 16 and the sprocket wheel carried thereby is lowered on the 15 beam 11, said counter-clockwise movement simultaneously expanding said spring 75 and building up a reverse tension. Thus when this head is released, the spring 75 tends to rotate the screw 73 in clockwise direction to elevate the frame 16 and 20 sprocket wheel 14, thus compensating for any slack which may occur in the chain 13.

The down-stroke of the pump piston 32 causes a suction in the conduit 54 and draws in a quantity of fluid through the inlet ports 58 and suction valve 56, the discharge valve 60 being in closed position. Now on the up-stroke of the piston 32, the suction valve 56 is in closed position and the column of fluid is forced upwardly 25 through conduit 55, past the discharge valve 60, through conduit 64 in the surge chamber and into the discharge line 61.

The surging of the fluid discharged from the pump is prevented by this surge chamber, wherein the piston 63 moves up and down taking on 35 any fluctuations of pressure and thus relieving the working parts of the pump from shock loads and insuring a uniform and steady flow in the discharge line 61. It will be noted that the piston 63 acting against the column of compressed air 40 in the upper portion of the chamber 62 serves as a cushion and opposes the pressure of the fluid passing through the conduit 64, said pressure being transmitted to the under-side of the piston 63 through the port 65.

45 In the drawings, I have shown a chain of the roller type but it is obvious that any other type of chain-drive may be employed and while I have shown gear-driving mechanism, I am aware that a worm-gear transmission may be employed and 50 also that two chains may be used if desired, one on either side of the main gear.

Furthermore, while I have illustrated a single-acting type of pump for simplicity's sake, a double-acting pump may be employed in connection 55 with my invention probably to a greater advantage, as with this type of pump the motor will run loaded at either stroke, better utilizing the motor power.

From the foregoing it is believed that the construction and advantages of my invention may be

clearly understood by those skilled in the art without further description, it being borne in mind that numerous changes may be made in the details of construction and operation without departing from the spirit of the invention as set forth in the following claims.

What I claim and desire to secure by Letters Patent is:—

1. A flexible transmission for driving a vertical electric submersible pump or the like comprising a vertically disposed cylindrical casing, a motor driven shaft extending into one end of said casing, a vertical beam in said casing, sprocket wheels carried by said beam, an endless chain running around said sprocket wheels, a gear transmission driven by said shaft and driving said endless chain, a vertically reciprocable rod extending into the other end of said casing, a guide-shoe supporting the end of said rod and running in a guide-way on said beam, means for operatively connecting said guide-shoe to a point on said endless chain, whereby the rotary motion of said shaft is transformed into a long stroke reciprocating motion for said rod, and means at the vertical extremities of said casing for connecting the same co-axially between a pump unit and a motor unit. 80 85 90 95 100

2. A flexible transmission as claimed in claim 1 including tension means for said chain.

3. A flexible transmission as claimed in claim 1 including tension means designed to normally force one of said sprocket wheels vertically away from the other of said sprocket wheels. 105

4. A flexible transmission as claimed in claim 1 wherein one of said sprocket wheels is carried in a frame slidably secured to said beam, and means for normally moving said sliding frame in a vertical direction away from the other sprocket wheel. 110

5. A flexible transmission as claimed in claim 1 115 wherein one of said sprocket wheels is carried in a frame slidably secured to said beam, and a spring loaded cam for normally forcing said sliding frame in a vertical direction away from the other sprocket wheel. 120

6. A flexible transmission for transforming the rotary movement of a prime mover into a long stroke reciprocating motion for a pump rod or the like comprising a vertically disposed cylindrical casing, a vertically extending support in said casing, sprocket wheels carried on said support in spaced relation, one of said sprocket wheels being operatively connected to said prime mover, a sprocket chain connecting said wheels, an arm having one of its ends connected to said chain 125 and its other end operatively connected to said pump rod, and means at the vertical extremities of said casing for connecting the same co-axially between a pump unit and a motor unit. 130

ARMAIS ARUTUNOFF. 135
